UNITED STATES PATENT OFFICE.

CHARLES E. HATHAWAY, OF PROVIDENCE, RHODE ISLAND, ASSIGNOR TO CUDGY-GARDNER COMPANY, OF PROVIDENCE, RHODE ISLAND, A CORPORATION OF RHODE ISLAND.

CLAMP.

Application filed November 1, 1924. Serial No. 747,188.

The present invention relates to display devices, and more particularly to racks for displaying linoleum rugs and the like.

No great difficulty is experienced in the display of woven rugs. According to the practice which has met with universal favor, an end of the rug is simply impaled upon a plurality of pins that stand up vertically from a supporting arm, and the arm is then raised, exposing the rug to full view in suspended condition. But a brittle material like linoleum can not be handled in any such way. The pins would puncture the rug; and if the pins be replaced by some other holding means, care must be taken that such holding means shall not fracture the linoleum. Even if a very slight indentation or other mark is produced, the rug can no longer be sold as a first-quality article. The act of suspending the rug, too, is liable to cause cracking of the linoleum if it is not properly held and the holding means properly raised. The difficulties attendant upon the problem will be appreciated from the fact that the only method of displaying linoleum rugs that has hitherto been used successfully is to roll them up and to stand the resulting rolls up on end, side by side. Naturally only a very small portion of the rug can be displayed in this manner.

The chief object of the present invention, therefore, is to provide a novel display rack particularly adapted for use with linoleum rugs and similar articles. A further object is to provide a novel clamp. Other and further objects will be explained hereinafter and will be particularly pointed out in the appended claims.

In the accompanying drawings, Fig. 1 is a side elevation partly broken away, and with parts in section, of a display device constructed according to a preferred embodiment of the present invention; Fig. 2 is a broken plan of the same, showing portions of the mechanism as occupying two positions, one in full lines and the other in dotted lines; Fig. 3 is a broken front elevation of a preferred clamp, upon a larger scale than Figs. 1 and 2; Fig. 4 is a corresponding rear elevation of the same; Fig. 5 is a side elevation of the same, looking from the left of Fig. 3, upon a further enlarged scale; and Fig. 6 is a section taken upon the lines 6-6 of Fig. 1, looking in the

direction of the arrows, upon the same scale as Fig. 5.

According to the display of the present invention, an edge margin 40 of a linoleum rug 42 is suitably mounted upon an arm 7, and the arm 7 is then moved away to cause the rug to open out to full view. It is preferred to have the arm 7 horizontal and to move it upward, so as to cause the rug to hang downward from the edge 40. Care should be taken not to crack or otherwise injure the fabric during the raising and lowering of the arm 7. The raising-and-lowering mechanism that is illustrated and described in United States Letters Patent No. 1,068,050, granted July 22, 1913, to Gardner and Chase has been found to operate admirably, and is therefore illustrated in the accompanying drawings. As the present invention is not restricted to the use of such specific mechanism, it will not be further described herein, reference being made to the said Letters Patent for a full description.

Of greater importance than the use of a suitable raising-and-lowering mechanism is the device employed for mounting the rug upon the arm 7. In fact, this mounting device may, in some cases, be employed upon a stationary arm 7. According to the preferred embodiment of the invention that is herein illustrated and described, the margin 40 of the rug is clamped between two jaws, each in the form of a strip as long as, or longer than, the edge 40. The strips are preferably constituted of sheet metal. One of the strips is provided with a body portion 44 and marginal flanges 46 and 48 disposed longitudinally of the strip and bent out of the plane of the strip in opposite directions at 50 and 52, respectively. The flanges 46 and 48 extend from the lines of bend 50 and 52 preferably at an incline to the plane of the strip, as shown more particularly in Figs. 5 and 6. The other strip is also provided with flanges 54 and 56, bent at 58 and 60, respectively, out of the plane body portion 62, preferably in the same direction. The flange 54 is bent into substantial parallelism with the body portion 62, preferably into contact therewith, to stiffen the strip. The flange 54 thus projects beyond the body portion 62. The other flange 56 also provides a stiffening action.

The strips are clamped together, with the edge 40 of the rug 42 between them, the longitudinally disposed line of bend 50 pressing against the rug on one side and the flange 54 on the other. The edge 64 of the flange 48 engages the body portion 62 near the flange 56. Entry of the linoleum between the strips is facilitated by the flange 46 diverging away from the other strip. The dimension of the flange 48 is such that the strips shall be in substantial parallelism, as illustrated in Figs. 5 and 6, when clamping a rug between them. The clamping surface is thus extended throughout a considerable area of both strips, preventing the cutting and biting into the rug that would otherwise obtain. As the strips are made of sheet metal, furthermore, the clamping action is more or less resilient, despite the large clamping area. The resiliency of the clamping effect is increased by the inclined position of the strip 48. Loosening of the clamp, due to its resiliency, is, however, prevented by the stiffening action provided by the flanges 54 and 56. A very effective clamp is thus provided, that clamps the margin of the linoleum rug over a comparatively large area, with a substantially uniform pressure, exerted resiliently, that results in very firmly holding the rug without any danger of causing injury thereto.

This desired result is brought about, notwithstanding the fact that the means for clamping the strip jaws together must be situated between the lines of bend 50 and 52 and entirely above the edge of the clamped margin 40 of the rug, as viewed in Figs. 5 and 6. The clamping means comprises a plurality of headed bolts 66, extending through longitudinally spaced, oppositely disposed, openings in the strips. Wing nuts 68 are threaded upon the bolts to clamp the strips together.

The strips are provided with additional, longitudinally spaced, oppositely disposed, openings 70, positioned between the flanges. The arm 7 is provided with correspondingly positioned projections 72 that are adapted to be received within the openings 70. The openings 70 and the projections 72 provide a convenient means for mounting the clamp upon the arm 7. The openings 70 have a lower portion of larger width than the upper portion, as shown more particularly in Figs. 3 and 4. The projections 72 may conveniently take the form of headed screws. The heads of the screws are of larger diameter than the width of the upper portions of the openings 70 but smaller than the width of the lower portions. When the clamps are mounted in position upon the arm 7, therefore, as illustrated in Fig. 1, the heads of the screws 72 prevent their accidental removal. Intentional removal of the clamps may be effected by merely lifting

the clamps to position the heads of the screws 72 opposite to the larger portions of the openings 70.

As will be clear from an inspection of Fig. 6, the linoleum clamp is supported on one side of the arm 7. A second series of projections 74 is provided on the other side of the arm 7, adapted to support a second clamp. Each arm 7 may thus support two rugs, visible from opposite sides of the arm. As is illustrated in Fig. 2, as many arms 7 may be mounted, side by side, as is desired each supporting two rugs. The arms 7 may be swung away from one another about pivotal points 2, as indicated in dotted lines, to afford a view of any particular rug. The compact, substantially flat, arrangement of the clamp strips permits a corresponding compact arrangement of the arms 7, neither the clamps nor the rugs supported thereby interfering with one another during the pivotal movement of the arms 7 about the pivotal points 2.

It will be understood that the invention is not restricted to the exact embodiment thereof that is illustrated and described herein, but that modifications may be made by persons skilled in the art without departing from its spirit and scope. It is therefore desired that the appended claims be broadly construed, except in so far as limitations may be imposed by the state of the art.

What is claimed is:

1. A clamp comprising two sheet-metal-strip jaws, one of the strips being provided with a body portion and marginal flanges disposed longitudinally of the strip and bent out of the plane of the body portion of the strip in opposite directions at an incline to the plane of the strip, the other strip having marginal flanges bent out of the plane of the strip in the same direction, one of the last-named flanges being bent into substantial parallelism with the strip, and means longitudinally disposed of the strips for clamping the strips together with the line of bend between one of the flanges and the body portion of the first-named strip in clamping engagement with the second-named flange of the second-named strip and with the edge of the other flange of the first-named strip in engagement with an intermediate portion of the second-named strip, the clamping means being positioned between the said line of bend and the edge of the said other flange of the first-named strip, and the strips being provided with oppositely disposed openings longitudinally spaced intermediate the flanges adapted to receive correspondingly spaced projections of a frame, whereby the clamp is adapted to be supported by the frame.

2. A clamp comprising two sheet-metal-strip jaws, one of the strips being provided with a body portion and marginal flanges

disposed longitudinally of the strip and bent out of the plane of the body portion of the strip in opposite directions at an incline to the plane of the strip, the other strip having 5 marginal flanges bent out of the plane of the strip in the same direction, one of the last-named flanges being bent into substantial parallelism with the strip, and means for clamping the strips together with the 10 line of bend between one of the flanges and

the body portion of the first-named strip in clamping engagement with the second-named flange of the second-named strip and with the edge of the other flange of the first-named strip in engagement with an intermediate portion of the second-named strip. 15

In testimony whereof, I have hereunto subscribed my name this 27th day of October, 1924.

CHARLES E. HATHAWAY.
